SUIT FOR DIVERS AND AN INTERCOMMUNICATION SYSTEM THEREFOR

Henry J. Burnett, 55 Glenbrook Road,
West Hartford, Conn.

Filed Nov. 6, 1958, Ser. No. 772,343
12 Claims. (Cl. 340—5)

This invention relates to an intercommunication system for divers and a diver's suit or other equipment in which said system is incorporated.

An object of the present invention is to provide an underwater intercommunication system which is particularly adapted for the transmission and reception of voices or other signals between divers while submerged in water.

A further object is the provision of such a system which is adapted for the reception of voices, or other signals, and which may be readily converted for transmitting a reply to said signals.

A further object of this invention is to provide such an underwater signal receiving system which may be quickly converted to a transmitting system by merely operating a pushbutton or other suitable means.

A still further object of this invention is the provision of a diver's suit that is equipped with my improved receiving and transmitting system.

Further objects and advantages of the present invention will be more fully understood from the following description and the accompanying drawing in which:

FIG. 1 is a diagrammatic view illustrating a diver's suit embodying the present invention.

FIG. 2 is a diagrammatic view of the electronic circuitry for the receiving and transmitting system of the present invention.

FIG. 3 is a sectional side view of a portion of a diver's suit embodying the present invention.

The receiving and transmitting system disclosed in the drawing hereof and to be herein described is a modification of the receiving and transmitting system described in my copending application Serial No. 784,919, filed January 5, 1959, and is particularly designed for use by such persons as frogmen, skin divers and the like while submerged in water; this invention being particularly intended for use in a diver's suit or with other equipment used by divers.

As shown in the drawing, the numeral 5 indicates generally, a receiving and transmitting device which may be enclosed in a suitable waterproof case 6 and which is preferably of a size that can be easily and conveniently carried by a diver underwater, or permanently installed in a suit or other equipment for divers.

The said device comprises electronic circuitry which includes an amplifying circuit 7 having a suitable number of preferably transistorized amplifying stages 8 to which are connected negative and positive electrodes 9 and 10, respectively. The said amplifying circuit is connected to a power output circuit 11 which includes a suitable two-way transformer 12 that is connectible to either a speaker 13 or to said electrodes 9 and 10 by means of a multi-pole two-way switch 15 which is selectively operated by a suitable manually operable member, such as a push-button indicated at 16.

In the use of the improved receiver and transmitter device above described, the said device is normally with the switch 15 in the position shown so that it is in condition to operate as a receiver for receiving electric signal currents carrying voice or other signals transmitted from a similar device used by another diver who wishes to communicate with the first diver. When the device is in such condition to receive, the signal currents are picked up by the electrodes 9 and 10 and carried through

2

the respective blades of the switch 15, through the amplifying circuit 7 and the power output circuit 11 and through the respective blade of said switch 15 to the speaker 13.

When the user of said device receives a signal from the other diver and he wishes to reply thereto, he immediately presses the button 16 and thereby moves the blades of the switch 15 to the position indicated in dotted lines and the device then becomes a transmitter. Upon sending the voice or signal, the electric currents will then pass from the transmitting microphone 14 through the amplifying system and through the power output circuit 11 to the electrodes 9 and 10 from which the electric currents will be transmitted through the water to the electrodes which are connected to a similar device operated by the second diver.

As illustrated in FIG. 1, the present invention also contemplates a diver's suit, indicated at 17, which is preferably constructed of rubber or other similar waterproof material and in which my above described improved receiving and transmitting system is incorporated, preferably in a permanent manner. Said suit has a body portion 18, leg portions 19 and a head portion 20. As shown, the receiving and transmitting device 5 is preferably mounted upon the body portion of the suit, near the chest, and shielded in such a manner that it is waterproof. If desired, the said device may be suitably mounted upon the inner side of the suit, as shown in FIG. 3, with the pushbutton 16 thereof disposed so that it may be operated by merely pressing upon the flexible portion 17-a of said suit to move said button and operate the switch 15 for converting the device into a transmitter as above described.

My improved diver's suit also includes a suitable earphone 13-a which is secured upon the inner wall of the head portion 20 in position to rest against the diver's ear, so that he may readily hear a signal sent by another diver.

The said diver's suit 17 also includes a transmitting throat microphone 14-a which is preferably mounted upon the neck portion 21 so that it will be in contact with the throat of the diver in said suit and will operate to transmit the diver's voice upon merely speaking in a natural manner.

Said suit also includes the electrode 10-b which is mounted in the head portion thereof and the electrode 9-b which is mounted in the foot portion of one of the legs 19 so that said electrodes are separated for the maximum distance possible to thereby render maximum efficiency in the reception and transmission of the electric signal currents through the water which is acting as the medium for conducting said currents.

Practically all of the transistorized circuitry, including the power source, such as the suitable batteries 22, is contained within the relatively small and compact case 6; the only members extending therefrom being the electrodes 9 and 10, which must be exposed and in direct contact with the water, the microphone 14 and the speaker 13.

If desired, the said case 6 may be mounted upon the exterior of the diver's suit and the button 16 may be operated through a flexible diaphragm or other suitable watertight means on the casing, not shown.

It will be understood from the above description and the accompanying drawing that my invention provides a diver's suit which contains an intercommunication device that is normally in condition to receive signals so that a diver will receive a message transmitted by another diver and the said set is then convertible, merely by pressing a button, such as 16, so that the entire set becomes a transmitter and will enable the diver to respond to the signal he has received. In this manner, a con-

versation, or exchange of signals, may be carried on between two or more divers within the range of the system by each diver merely operating the pushbutton 16 when he wishes to respond.

Also if desired, my improved receiving and transmitting system may be readily adapted for use by skin divers, for which use, the case 6 may be mounted by suitable means upon the body of the diver or his diving equipment, and the microphone and speaker may be, respectively, mounted so that they are disposed close to the throat and ear of said diver.

I claim:

1. An electronic system for receiving and transmitting signals under water which includes electronic circuitry providing an amplifying circuit, a power output circuit connected to said amplifying circuit, a pair of electrodes, a transmitting microphone, a speaker, and a multi-pole switch adapted to selectively connect one of said electrodes to said amplifying circuit and said speaker to said power output circuit for rendering said circuitry operable for the reception of signals through said speaker, or connect said microphone to said amplifying circuit and said electrode to said power output circuit to render said circuitry operable for the transmission of signals through said microphone.
2. A receiving and transmitting system including an electronic device having an amplifying circuit, a power output circuit including a transformer connected to said amplifying circuit, an electrode connected to said amplifying circuit, a separate electrode, a speaker, a microphone, and a multi-pole manually operable switch for selectively connecting said separate electrode to said amplifying circuit and said speaker to said transformer for receiving signals, or connecting said separate electrode to said transformer and said microphone to said amplifying circuit to render said system operable for transmitting signals.
3. A receiving and transmitting system including an electronic device having an amplifying circuit, a power output circuit connected to said amplifying circuit, an electrode connected to said amplifying circuit, a separate electrode, a speaker, a microphone, and a manually operable switch having a plurality of poles, one of said poles being adapted for connecting said separate electrode to one side of said amplifier and to said power output circuit, another of said poles being adapted to connect said speaker to said power output circuit and another of said poles being adapted to connect said microphone to the said amplifying circuit, the said switch being normally in position wherein the separate electrode is connected to the amplifying circuit and the speaker is connected to the power output circuit for receiving signals, and means for operating said switch into position wherein the said microphone is connected to the amplifying circuit and the separate electrode is connected to said power circuit to render said system operable for transmitting signals.
4. In a diver's suit, a receiving and transmitting system including an electronic device mounted to the body portion of said suit, electrodes connected to said device and mounted upon the head and foot portions of said suit and exposed for direct contact with water, a microphone mounted upon the interior of said suit in position to contact the throat of the diver, an earphone mounted in the head portion of said suit for proximity to the ear of the diver, and switch means operable by the diver from the

exterior of the suit for converting said system for the transmission or reception of signals.

5. In a diver's suit constructed of flexible sheet material, a receiving and transmitting system including an electronic device containing amplifying circuitry and mounted within said suit adjacent a flexible wall portion thereof, and switch means on said device including a movable member operable by flexing movement of said wall portion when pressure is applied upon the exterior thereof.

6. In a diver's suit having body, head and neck portions and a pair of foot portions; the combination of an electronic receiving and transmitting system including amplifying circuitry contained within a case mounted adjacent said body portion, a pair of electrodes exposed exteriorly of said suit for direct contact with the water in which said suit is submerged, one of said electrodes being mounted upon said head portion and the other on one of said foot portions, a speaker mounted on said head portion, and a microphone disposed on said neck portion.

7. In a diver's suit having body and head portions; the combination of an electronic signal receiving system including amplifying circuitry contained within a case mounted upon said body portion; said circuitry including a speaker in said head portion, and a pair of spaced electrodes exposed exteriorly of said suit for direct contact with water in which said suit is submerged.

8. In a diver's suit having body and neck portions; the combination of an electronic signal transmitting system including circuitry contained within a case mounted upon said body portion, said circuitry including a microphone in said neck portion, and a pair of spaced electrodes exposed exteriorly of said suit for direct contact with water in which said suit is submerged.

9. The subject matter set forth in claim 8 wherein said electrodes are mounted upon spaced portions of said suit.

10. In a diver's suit, the combination of an electronic signal receiving and transmitting system including circuitry carried by said suit; said circuitry having connected thereto a speaker, a microphone, and a pair of spaced electrodes exposed exteriorly of said suit for direct contact with water in which said suit is submerged.

11. The subject matter set forth in claim 10 wherein said electrodes are mounted upon spaced portions of said suit.

12. An electronic system for the reception and transmission of signals by a diver under water; said system including electronic circuitry providing amplifying means contained within a case having connected thereto a pair of electrodes, a transmitting microphone and a speaker, manually operable means in said case for converting said circuitry for the reception or transmission of signals, means for mounting said case upon the body of the diver within reach of his hand, means for mounting said microphone adjacent to the diver's throat, means for mounting said speaker adjacent said diver's ear, and means whereby said electrodes are carried by said diver in spaced apart positions.
